TEST TUBE RACK

Philip M. Seymour, 1920 Mershon,
Ann Arbor, Mich. 48103

Filed Dec. 7, 1966, Ser. No. 4,955

Term of patent 14 years

(Cl. D16—1)

FIG. 1

FIG. 2

FIG. 3

FIG. 4

FIGURE 1 is a top plan view of a test tube rack showing my new design;

FIGURE 2 is a front elevation thereof;

FIGURE 3 is a rear elevation thereof; and

FIGURE 4 is a side elevation thereof as seen from the right side of FIGURE 1.

I claim:

The ornamental design of a test tube rack, as shown.
